UNITED STATES PATENT OFFICE.

JAMES YOUNG DOWNING, OF JACKSON, MISSISSIPPI.

DRY-GOODS-MEASURING MACHINE.

Application filed July 23, 1924. Serial No. 728,759.

This invention relates to a cloth handling machine, the general object of the invention being to provide means whereby cloth and the like can be taken from the flat bolts in which it comes from the manufacturer and wound upon tubes so that it can be more easily handled and stored and will be less liable to deteriorate than when kept in the bolt form.

Another object of the invention is to provide means for measuring the cloth as it is being sold or when received from the manufacturer.

A further object of the invention is to provide means for rolling up with the cloth a measuring strip which facilitates the measuring of the cloth when the same is being sold.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is an elevation of one arrangement of carrying out the invention.

Figure 2 is a transverse sectional view through Figure 1.

Figure 3 is a detail plan view of the automatic stopping mechanism for operating the measuring board by a motor.

Figure 4 is an elevation of such means.

Figure 5 is a section on line 5—5 of Figure 3, one of the gears connecting the machine with the motor being shown in elevation.

Figure 6 is a section on line 6—6 of Figure 3, the operating disk being shown in elevation.

Figure 7 is a sectional view taken at right angles to Figure 6, the operating disk being shown in elevation.

Figure 7^a is an enlarged detail view of the alarm mechanism.

Figure 8 is an end view of such mechanism.

Figure 9 is a detail plan view of parts of such mechanism.

Figure 10 is a view of a supporting rack for a number of rolls of material.

As is well known the bolts of cloth are of

flat formation as they come from the manufacturer, as shown at A in Figures 1 and 2, the cloth being wound around a strip or board 1 of paste board or other material. 60 These bolts are usually placed on shelves and are piled one upon another so that it is very difficult to handle the bolts as they must be taken from the shelves and piled upon the counter in order to show the goods to the 65 customer. The goods deteriorates very rapidly under these conditions and each bolt must be handled in order to display the goods to the customer. It is the object of my invention to rewind the goods upon tubes 70 so that the tubes can be placed in display racks in such a manner that they will rotate so that the goods can be readily inspected and portions taken from the rolls without difficulty. In carrying out my invention I provide a supporting framework 75 2 which may be a cabinet, and place a rod 3 in the upper part thereof which slidably supports a depending frame 4 which carries the pointed pinte 5, a similar pinte 6 being 80 carried by the cabinet 2 so that a bolt of cloth A may be rotatably supported by the pintles by having the pointed ends of said pintles penetrate the ends of the strip 1. 85 As the frame 4 is slidably mounted on the rod 3, bolts of different lengths may be used in the device. I prefer to place a spring 7 on the rod 3 and to connect one end thereof with the cabinet and its other end with the frame 4 so that the frame will adjust itself to the length of the bolt being 90 operated upon. A pinte 8 is carried by a spring member 9 which is fastened to the end of the cabinet under the pinte 6 and a stub shaft 10 is journaled in the lower end 95 of the frame 4 and is provided with a handle 11 and with a disc 12.

A spring 13 on the shaft, and arranged between the disc 12 and the frame 4, tends to move the shaft longitudinally until its handle 11 engages the frame 4 and prevents further movement of the shaft. The pinte 8 and the inner end of the shaft 10 are adapted to engage sockets 14 formed in the ends of a tube 15, the socket for the shaft 10 being of rectangular shape and the end of said shaft being of similar shape so that the tube 15 will be rotated with the shaft 10 when the handle 11 is turned.

Thus when the bolt is placed on the pintles 110 5 and 6 and a tube 15 put in position below the same and the end of the cloth fastened

to the tube 15 by turning the handle 11, the cloth will be rolled from the bolt upon the tube 15 and when said tube 15 is full it may be placed in a cabinet or other support 5 which is provided with projections for engaging the sockets 14 so that the roll of cloth will be rotatably supported and the goods can be easily inspected or portions cut from the roll by rotating the roll. The tubes 10 can be supported on the support B' shown in Figure 10, which is provided with the hooks α for receiving the ends of the tube 15.

I may also place a small roll 16 adjacent the tube 15, this roll 16 being adapted to contain 15 a strip having scales thereon and which is adapted to be wound up with the cloth on the tube 15 so that when the cloth is unwound the tape will also be unwound and thus act as means for removing from the roll 20 of cloth the desired amount of material, the strip taking the place of a measuring rule.

In order to facilitate the sale of the goods I provide a measuring board 17 which has a socket at one end adapted to receive the 25 pintle 18 carried by the spring strip 19 and which has a long socket 20 at its other end for receiving the spindle 21 which is connected with the worm shaft 22 carried by the journals 23 and which is adapted to be 30 driven from the motor 24 by the gears 25 and the friction clutch 26. This board 17 is provided with a clip 27 which serves as a means of connecting the end of the cloth to the board and the board is preferably of a 35 width equal to a half yard so that two turns of cloth around the board will give approximately a yard of material. Four turns would give approximately two yards so that each time the board is rotated a complete 40 revolution approximately a yard of material is wrapped on the same. Of course the board can be made of other dimensions than a half yard.

The shaft 22 is provided with a spiral 45 thread 28 and a hole 29. A block 30 is slidably mounted in the frame 31 which is provided with graduations 32 which cooperate with a marker 33 on the block. A stem 34 is longitudinally movable in the block and it 50 has a notch 35 in its end for engaging the thread 28 on shaft 22. The stem 34 is adapted to be projected into the hole 29 in the shaft 22 when it rides from one end of the thread 28 so as to stop the movement of the 55 shaft 22 by holding the same against rotation while the clutch 26 slips over the end of the shaft 22. A cross piece 36 is carried by the stem and pins 37 are carried by the cross piece and extend into holes 38 formed in the 60 block. Springs 39 on the pins tend to hold the stem in engagement with the threads and to force it into the opening 29 when it comes opposite the same. A knurled disc handle 40 is rotatably mounted on the end of the stem 65 and a cam 41 on said handle coacts with a

cam 42 on the block. It will be apparent from the illustrations 6 and 7 that the springs 39 bearing against the cross piece 36 will normally retain the stem 34 into engagement with the thread 28 until the stems 70 become aligned with the opening 29, at which time the tension of the springs will project the stems into this opening to prevent further rotation of the shaft 22 and in order to remove the stem from the opening 75 to reset the block 30, the disk 40 is rotated so that the action of the cams 41 and 42 will withdraw the stem from the opening 29.

It will thus be seen that the motor will continue to operate the board 17 until the 80 stem leaves the thread and enters the hole 29 when further movement of the shaft 22 will be prevented and the board 17 will come to rest. Thus the parts can be set by means of the scale 32 so that the correct amount 85 of goods will be wound upon the board and then the board will cease to rotate. I also provide means for sounding an alarm when a certain amount of material has been unwound from a roll. Such means consists of a shaft 43 rotatably mounted in the frame 90 and having the friction rolls 44 thereon which are engaged by the cloth so that the shaft will be rotated as the cloth passes over the rolls and under a guiding shaft 45 95 on its way to the board 17. One of the rolls 44 is adjustably mounted on the shaft 43, as shown. The shaft 43 is connected by the gears 46 with the shaft 47 of a disc 48 which carries the dial 49. The shaft 47 is supported upon a bearing bracket carried by the cabinet 42 as clearly illustrated in Figures 7^a and 8. A marker 50 is associated with the dial and a block 51 on the disc is adapted to close the switch 52 on a support 100 53 which controls the circuit 54 of an alarm 55. Thus every time the block 51 comes opposite the switch the alarm will be sounded. The switch member 52 includes a stationary 105 and a resilient contact, the resilient contact being normally positioned in the path of the block 51 so that after the disk 48 rotates and brings the block 51 into engagement with the resilient contact this contact will be forced into engagement with the stationary contact in order to close the circuit 110 and after the block 51 is moved out of engagement with the spring contact the said spring contact will be returned to its engagement relative to the stationary contact. This device is useful in measuring in taking 115 stock or as it comes from the manufacturer and the alarm will ring as every ten yards is unwrapped from the bolt. Of course this arrangement could be used for measuring small pieces of material as the dial could be set in relation to the marker 50 so that the bell would ring when a certain amount of material has been unrolled. While this device is shown as associated with the board 120 125 130

17 it will be understood that a tube similar to the tube 15 could be used in place of the board 17 so that the goods could be wound upon such tube and the goods passing over 5 the rolls 44 of the shaft 43 would actuate the alarm as before explained. The goods can be rolled directly from the bolt on to the board 17 or upon a tube used in place of said board or the goods could be unrolled 10 from a tube similar to the tube 15 and placed in a similar position as said tube 15.

I prefer to provide the board 17 with a chart 17' and with a sliding cost scale 17* for facilitating the cost of different pieces 15 of material at different prices.

From the foregoing it will be seen that I have provided means whereby cloth can be easily and quickly wound upon tubes or shafts and also means for measuring the 20 cloth as it is being unwound.

Figure 2 shows supporting members 60 in the supporting cabinet for the bolts. These supports may be of any desired type and could be placed in other cabinets or sup-

ports which do not contain the winding apparatus.

It is thought from the foregoing description that the advantages and novel features of my invention will be readily apparent.

I desire it to be understood that I may 30 make changes in the construction and in the combination and arrangement of the several parts, provided that such changes fall within the scope of the appended claim.

What I claim is:—

A device of the class described including a supporting frame, means detachably, removably and rotatably supporting a bolt of material in the frame, a tube removably supported in the same beneath the bolt supporting means, means whereby to impart rotative movement to said tube for winding material thereon from the bolt and means disposed between the layer of material as it is wound upon the tube whereby to measure 40 said material when removed from the tube.

In testimony whereof I affix my signature.

JAMES YOUNG DOWNING.
